UNITED STATES PATENT OFFICE.

JOSEPH H. MOSEL, OF LAKewood, OHIO, ASSIGNOR TO THE LAKewood ENGINEERING COMPANY, OF CLEVELAND, OHIO, A CORPORATION OF OHIO.

TOWER ERECTION DERRICK.

Application filed March 14, 1921. Serial No. 452,374.

To all whom it may concern:

Be it known that I, JOSEPH H. MOSEL, a citizen of the United States, residing at Lakewood, in the county of Cuyahoga and State of Ohio, have invented a certain new and useful Improvement in Tower Erection Derricks, of which the following is a full, clear, and exact description.

The present invention relates to an apparatus useful in the erection of towers, and as an example of such towers, mention may be made of towers used in the construction of buildings or similar structures where concrete mixed on the ground is elevated on the tower to a given height and distributed through chutes to different parts of the construction which is being built. Mention of these particular towers is made without in any way limiting the invention, as the invention is broader than the specific use, as will later appear.

The invention may be briefly described as comprising an erection device which is moved upward upon the tower construction as the same is erected. This erection unit is provided with platforms upon which workmen may stand for the purpose of securing the parts of the tower in the process of erection and additionally the erection device is provided with a hoist mechanism by which the material entering into the construction of the tower may be hoisted from the ground and elevated to proper position for its incorporation into the tower structure.

The invention further contemplates an erection device which upon completion of the tower may be lowered, preferably within the tower to the ground and there disassembled.

Various features and further objects of the invention will appear as the description proceeds.

Reference should be had to the accompanying drawings forming a part of this specification, in which Fig. 1 is an elevation showing an erecting device of the present invention in cooperating position with the tower which is being erected. Fig. 2 is a side elevation. Fig. 3 is a plan view substantially along the line 3—3 of Fig. 1. Fig. 4 is a sectional plan showing a detail of construction. Fig. 5 is an elevation showing a unit which forms a part of the tower construction. Fig. 6 is an elevation

showing another unit of the tower construction.

Referring to the drawings, 1 indicates what may broadly be termed a tower which is made of suitable structural elements 60 which in the present instance are largely angle irons suitably held together by bolts and braced by tie-rods.

In Figs. 5 and 6 there are illustrated two units which enter into the particular tower structure which is illustrated in the drawings. In Fig. 5 the unit 2 illustrated is such as is used to form the front and rear elements of a tower section. Fig. 6 represents a unit which may form one side of the tower section and a unit similar to that shown in Fig. 6 may form the other side. These sections which enter into the construction of the particular tower which is illustrated are merely described for the purpose of more clearly indicating the use of the invention and are not to be taken as limiting but merely indicative of any tower construction.

The tower construction illustrated is provided with guides which extend vertically, these guides being indicated at 3 in Fig. 6, and it will be understood that on the element which forms the opposite side of the tower, there will be guides such as indicated at 4 in Fig. 3. These guides in the tower are for the purpose of forming guiding elements for an elevator or bucket which is adapted to be raised and lowered for the purpose of elevating building material to be used in the construction of the building. It will be obvious that where the tower is used for other purposes these guides may be omitted.

The erecting device which forms the real subject matter of the invention has transversely extending angle bars 5 and 6 and secured to these members 5 and 6 adjacent the ends thereof and extending in a direction at right angles to the members 5 and 6 are what we may term platform members 7 and 8, because these members adjacent one end are adapted to support a platform 9, this platform serving as standing room for workmen who are erecting the tower. Secured to the ends of the members 7 and 8 are upwardly extending members 10 and 11, and 10^a and 11^a which converge and at their upper ends are joined to each other by means of plates such as indicated at 12. to the upwardly extending members 10, 11, 10^a and 11^a, are transversely extending members, preferably made of angle iron such as indicated at 13, and these members 5 at their end portions support platforms such as indicated at 14, these serving as standing room for the workmen erecting the tower.

There are also other angle iron pieces such 10 as indicated at 15 which connect the members 10, 11, 10^a and 11^a, for the purpose of strengthening the structure and these members also serve as a means for climbing from the platform 9 up to the platform 14. At 15 the ends of the members 5 and 6 as shown in Fig. 3 there are vertically extending members 16, 17, 16^a and 17^a. These members at one of their ends are attached by suitable means to the transversely extending 20 members 5 and 6 and to the members 7 and 8. These guide members which have been described are in position to cooperate with the guide members 3 and 4 which form parts of the tower construction. That is to say, 25 they are sufficiently close to the tower guide members so that as the erecting device is raised or lowered the device is guided by the cooperation between the guide members 3 and 4 and the members 16, 17, 16^a and 17^a 30 carried by the erecting device. These vertically extending guide members at their lower ends are joined by plates indicated at 18 in Fig. 1 and extending between the plates 18 are transversely extending members 19. Furthermore there are members 35 extending diagonally upward from the plates 18 such as indicated at 20 in Fig. 1 which extend from the members 7 and 8, or rather from the plates such as 8^a, to which they 40 are secured and which plates are in turn secured to the members 7 and 8. These diagonally upward extending members 20 at their lower ends connect with the plates 18, thus 45 forming a rigid connecting means between the lower ends of the guide members 16, 17, 16^a and 17^a and the members 5, 6, 7, and 8.

Pivoted upon the vertical guide members 16, 17, 16^a and 17^a are supporting dogs indicated at 21, there being two such dogs 50 which are oppositely disposed and the dogs are pivoted to the erecting device as indicated at 21^a. Each of the dogs comprises two spaced members 21^b and 21^c such as shown in Fig. 3 and these members just mentioned are joined by a rod 22 which lies above the transversely extending members 5 and 6. The lower, or outer ends of the dogs are of sufficient length to rest upon the upper portion of the tower construction, in 55 the present instance resting upon the top angle iron of the uppermost tower section which has been assembled, and these dogs serve to support the erecting device upon the tower. It will be apparent that when, as 60 later described, the erecting device is ele-

vated through tower sections which have been newly added the outer ends of the dogs will be pushed down and out of the way if the outer ends engage with parts of the tower structure, and due to the fact that 70 there is greater weight at the inner ends of the dogs where the rods 22 are situated, the natural tendency of the dogs will be to assume the position shown in Fig. 2.

In order to hold the erection device from 75 slight movement or vibration when cooperating with a tower, means may be provided for this purpose, and in Fig. 4 one way is indicated in which this may be accomplished. Set screws such as indicated at 23 80 may be threaded through suitable openings in the guide members 16, as well as through the other guide members which may be moved into position against the guides 4 on the tower, and by locating these set screws 85 such as 23 for instance, at the extremities of the guide members 16, 17, 16^a and 17^a, the erection device will be held against vibrating movement.

Extending centrally through the erection 90 device is a member 24. This element is preferably a hollow pipe-like structure, at its lower end there is a collar 24^a which bears against a thrust plate 25 which is supported on the members 5 and 6. This thrust 95 plate has a central opening through which the member 24 extends. This construction described serves to mount the end of the member 24 in a fashion which permits rotation of this member. The member 24 extends through an opening in the plate 12 which joins the upper ends of the members 10, 11, 10^a and 11^a as above described, this construction being for the purpose of forming 100 an upper guide and retention member 105 for the member 24.

Upon the upper end of the member 24 which extends beyond the plate 12 there is mounted a suitable hoisting mechanism. This hoisting mechanism in the present instance comprises transversely extending angle members 25 and 25^a. These angle members are pivotally mounted upon the member 24 as indicated at 26. At the ends of the members 25 and 25^a there are diagonally 110 extending straps 27 and 27^a and oppositely disposed with respect thereto is a pair of straps one of which is indicated at 28. These straps at their lower ends are secured to suitable plates 29 which are in turn connected to the member 24 just above the plate 12. The ends of the straps 27 and 27^a and the oppositely disposed straps 28 and 28^a are so arranged that the connection with the plate 29 may be removed so that the whole structure which has just been described, to-wit, the members 25, 25^a, 27 and 27^a and the pair of oppositely disposed straps 28 and 28^a may move pivotally about the point 26. This construction is purposeful in that it permits 120 125 130

the entire erecting device to be moved downwardly through the tower after the complete erection thereof, which would otherwise not be possible due to the fact that the member 5 25 at the end of the member 24 extends beyond the sides of the tower. At the ends of the members 25 and 25^a there are pulleys 30 and 31 and there is a pulley 32 which is mounted between the plates 29 and adjacent 10 the point where the members 27 and 28 are connected to the plates 29.

Extending over the pulleys which have just been described is a hoisting cable 33 and if desired this cable after passing over 15 the pulley 32 may pass through a suitable opening into the tubular member 24 and down to the bottom of the tower to the hoisting apparatus. This construction permits the hoisting cable to be centrally arranged 20 within the tower and thus out of the way.

And inasmuch as the end of the hoisting cable 33 is in certain positions beyond the sides of the tower, there is provided a block and tackle arrangement for pulling in the 25 lower end of the cable. This comprises a pulley 34 and an opposite pulley 35 which pulleys are respectively attached to the end of the cable 33 and to the member 24.

It will be seen that due to the mounting 30 of the member 24 the whole hoisting apparatus which has just been described is located so that the hoisting end of the cable 33 may be moved so as to position the various parts of the tower which is being erected.

35 At the lower portion of the erecting device as for instance upon the oppositely disposed plates 18 there are secured pulleys 36 and 37. The rope or cable which passes over these pulleys is passed around other pulleys such as indicated at 38 and 39 which pulleys and cable are for the purpose of moving the erecting device upward within the sections of the tower which have been completed.

40 In the illustration of Fig. 1 we may assume that the erecting apparatus has just been elevated upon a completed section of the tower, and in this position the next section of the tower may be erected by the workmen from the platforms 9 and 14, utilizing the hoisting apparatus before described to elevate the sections of the tower which are to be placed. When the additional tower section is completed, as represented 45 by the dotted lines in Figs. 1 and 2, the pulleys 38 and 39 will be attached to the upper part of the tower section which has been completed, and by this means the entire erecting device may be raised as a unit. The 50 raising operation continues until the dogs 21 are in position to engage above the upper side members of the tower section which has been erected in a similar position to that shown in Fig. 2. During this operation the movement of the erecting device is guided

through the engagement between the guide members 16, 17, 16^a and 17^a on the erecting device and the guides 3 and 4 on the tower.

When the erecting device is elevated as described the platforms 9 and 14 and the 5 70 hoisting mechanism associated with the erecting device are all above the completed portions of the tower, and the guide members on the erecting device which cooperate with the guide members on the tower have a sufficient length of engagement so as to insure that there will be no tipping action of the upper portion of the erecting device.

75 The erecting device is elevated as the successive sections of the tower are erected and when the tower is completed, the straps 27 and 28 and their associated straps may be disengaged from the plates 29 which permits these members together with the members 25 and 25^a to assume the position shown in dotted lines in Fig. 1, in which position the entire erecting device may be lowered within the tower, to the lower end of the tower and there disassembled and removed.

80 While in the present construction as described the guide members such as those indicated at 16, 17, 16^a and 17^a have the erecting device cooperated with the guide members such as 3 and 4 carried by the tower, it will be understood that this particular construction is not essential, as the erecting device may be guided by engagement with other portions of the tower than that specifically pointed out.

85 Having described my invention, I claim: 100

1. The combination with a skeleton tower adapted to be built up in superposed sections, said sections having aligned vertical guide members forming a guideway, of an 105 erection device comprising a rigid frame slidably mounted in the vertical guideway of the tower and provided with a platform, said erection device having hoisting means above said platform, and means for securing said erection device in adjusted positions on the tower.

2. The combination with a skeleton tower adapted to be built up in superposed sections, said sections having secured to opposite sides upon the interior thereof, aligned vertical guide 115 members forming guideways, of an erection device comprising a rigid frame mounted for vertical movement within the tower and having on opposite sides thereof guide members engaging the guideways, said frame having a platform mounted upon the upper portion thereof and said erection device having hoisting means above the platform, and means for raising and lowering the frame in the tower and for securing the same in adjusted 120 positions.

3. An erecting device adapted for use in 125 erecting a tower, comprising a frame having a transversely extending central member, depending guide members from the central 130

members, braces connecting the lower ends of the said guide members with the said central member, converging diagonal members extending above the central member, means for retaining the upper ends of said converging members and a platform supported from the said converging members.

4. An erecting device adapted for use in erecting a tower, comprising a frame having 10 a transversely extending central member, depending guide members from the central members, braces connecting the lower ends of the said guide members with the said central member, converging diagonal members 15 extending above the central member, means for retaining the upper ends of said converging members, a platform supported from the said converging members, a tubular member extending centrally with respect to the 20 frame and rotatably supported by said transverse member at the central portion of the frame, means at the upper ends of the converging members for retaining the said tubular member and a hoisting member mounted upon the said tubular member.

5. An erecting device adapted for use in erecting a tower, comprising a frame having a transversely extending central member, depending guide members from the central 25

member, braces connecting the lower ends of the said guide members with the said central member, converging members extending above the central member, means for retaining the upper ends of said diagonal members and a platform supported from the said converging members, a tubular member extending centrally with respect to the frame and supported by the transverse member at the central portion of the frame and supported for rotation, means at the upper ends 30 of the converging members for supporting the said tubular member, and transversely extending member pivotally mounted upon the upper end of said tubular member, tie 35 rod members connecting the opposite ends 40 of the said transversely extending member to the tubular member, the said tie rods being detachable, whereby the transversely extending member may be turned about its pivot, pulleys mounted at the opposite ends 45 of the transversely extending member and a pulley mounted upon the tubular member and adjacent thereto and a hoisting rope extending around said pulleys and through the 50 tubular member.

In testimony whereof, I hereunto affix my signature.

JOSEPH H. MOSEL.
